RAILWAY TRAFFIC CONTROLLING APPARATUS 5

Clifford D. Ihrig, Penn Township, Allegheny County, Pa., assignor to Westinghouse Air Brake Company, a corporation of Pennsylvania

Application March 22, 1951, Serial No. 216,953

10

10 Claims. (Cl. 246—26)

My invention relates to railway traffic controlling apparatus. More particularly, my invention relates to apparatus of the type which is known as traffic locking apparatus, by means of which traffic governing devices such, for example, as signals, for any given stretch of railway track, are, in part, manually controllable for governing traffic movements in both directions, and by means of which the traffic governing devices, after being controlled for governing traffic movements in one direction or the other over the stretch of railway track, cannot be controlled for governing traffic movements in the opposite direction while the stretch of track is occupied by a train.

One form of traffic locking apparatus, which has been used, requires joint action by persons at two different control stations for manually controlling traffic movements in both directions over a stretch of railway track. Each of the two control stations may be provided with an interlocking machine, and each of the interlocking machines may be equipped with a traffic lever which is mechanically interlocked with a signal lever which controls a signal for governing traffic movements onto the corresponding end of the stretch of railway track.

In apparatus embodying my invention, no separate traffic levers are employed. Instead, traffic direction controlling apparatus, in my invention, is controlled by manually controllable signal relays which also control the signals for governing traffic movements onto the opposite ends of the stretch of railway track.

In some forms of traffic locking apparatus, a traffic control circuit arrangement has been employed, which embodies two conductors extending between the opposite ends of the associated stretch of railway track. In this control circuit arrangement, a plurality of polar traffic control relays, one for each signal location, are energized in series by current of one polarity or the other. With such forms of traffic locking apparatus, the associated stretch of railway track may be divided into a plurality of track sections, each of which is provided with a track circuit including the rails of the section, and a suitable source of current connected across the rails adjacent one end of the section, and also including a neutral track relay connected across the rails adjacent the opposite end of the section. A front contact of each of these track relays is included in the traffic locking circuit arrangement. Line control circuits for the signals are controlled by contacts of the track relays and by contacts of the polar traffic control relays.

In a later form of traffic locking apparatus, in which also a plurality of polar traffic control relays are energized in series in a traffic control circuit, two track circuits, which may be of the coded type, are employed for each track section, one for each direction of traffic movement. The track circuits for a given direction of traffic movement are set up by contacts of the polar traffic control relays when closed in a given or normal position in response to energization of the polar traffic control relays by current of a given normal polarity, and the track circuits for the opposite direction of traffic movement are set up by con-

2

tacts of the polar traffic control relays when closed in the opposite or reverse position in response to energization of the polar traffic control relays by current of the opposite or reverse polarity. It has been found that, with this later scheme, if contacts of the track relays or of relays controlled by the track relays are included in the traffic control circuit arrangement similarly to the way they are included in the earlier schemes, a locked-out condition of the traffic control circuits may occur under some conditions. If, for example, the contacts of one or more of the polar traffic control relays should become misplaced by an induced surge of foreign current, one or more track relays would become deenergized, and the traffic control circuits would not be self-restoring.

An object of my invention is therefore the provision of means for making the misplacement of the polar contacts of the polar traffic control relays in a series traffic control circuit less likely to occur.

A feature of my invention for attaining this object is the provision of an arrangement for keeping the polar traffic control relays energized while the associated stretch of railway track is occupied by a train, or while a signal is controlled to display a proceed indication for a train to enter the associated stretch of railway track.

Another feature of my invention for attaining this object is the provision of an arrangement for keeping the polar traffic control relays energized, while the associated stretch of railway track is occupied by a train, by current of the same polarity as that by which they were energized when the train entered the stretch of track, and when a signal was cleared for directing the train to enter the stretch of track.

Another object of my invention is the provision of means by which a traffic control circuit will be rendered self-restoring in the event of the polar contacts of one or more of the polar traffic control relays which are included in series in the traffic control circuit becoming misplaced in some way such, for example, as by a surge of current induced from a foreign source of power while the traffic control circuit is deenergized.

A feature of my invention for attaining this object is the provision of auxiliary means for closing a traffic control circuit in response to misplacement of the polar contacts of a polar traffic control relay.

Still another object of my invention is the provision of means for restoring the traffic control circuit to an operative condition in the event of a locked-out condition being caused by some unusual occurrence.

A feature of my invention for attaining this object is the provision of an arrangement for restoring a traffic control circuit to an operative condition by energization of the manually controllable signal relay for the entering signal for either end of the associated stretch of track.

Another object of my invention is the provision of means for checking the condition of the traffic controlling apparatus after each reversal of polarity of the current by which the traffic control circuit is energized.

A feature of my invention for attaining this object is the provision of two stick relays, one for each end of the stretch of track, each of which can become energized only when the contacts of the polar traffic control relay for a signal adjacent the corresponding end of the associated stretch of railway track are in the position for controlling the apparatus to direct a train to enter the stretch of railway track at that end, and only when the track circuits have been set up for a train moving onto the stretch of track in the corresponding direction, and also only when the stretch of track is unoccupied. Each of the two stick relays will then remain energized regardless of occupancy of the stretch of track by a train until the contacts of the polar traffic control relays are moved to the opposite position.

I shall describe one form of apparatus embodying my invention, and shall then point out the novel features thereof in claims.

In the accompanying drawings, Figs. 1a, 1b, 1c and 1d, when placed end to end in the order named, with Fig. 1a on the left, constitute a diagrammatic view showing one form of apparatus embodying my invention for a stretch of railway track which is provided with a plurality of signals for governing traffic movements in opposite directions over the stretch of railway track; which embodies a plurality of polar traffic control relays, one for each of given signal locations, connected in series, each of the polar traffic control relays having one or more contacts which, when the corresponding relay becomes deenergized, remain closed in the normal or the reverse position to which they were last previously operated in response to current of normal or reverse polarity; in which two sources of current of similar potential, one adjacent each end of the stretch of track, are connected in opposition to each other in series with the polar traffic control relays, so that the polar traffic control relays are normally not energized; in which operation of manually controllable signal control means for a given end of the stretch of track effects energization of the polar traffic control relays by current of a given polarity from the source of current for the opposite end of the stretch, and operation of manually controllable signal control means for the opposite end of the stretch effects energization of the polar traffic control relays by current of the opposite polarity from the source of current at the given end of the stretch; in which the polar traffic control relays are retained energized by current from one or the other of the two sources of current while the stretch of track is occupied by a train; and in which the signals for a given direction of traffic movements are controlled by means including contacts of the polar traffic control relays closed in a given normal position, and the signals for the opposite direction of traffic movements are controlled by means including the contacts of the polar traffic control relays closed in the opposite or reverse position.

Similar reference characters refer to similar parts in the drawings.

Referring to the drawings, a stretch of main railway track X is shown connected, adjacent one of its ends, with an auxiliary track U, by a switch designated by the reference character 1, and is shown connected, at its opposite end, with a second auxiliary track, designated by the reference character Z, by a second switch designated by the reference character 5.

The stretch of track X is divided by insulated joints 7, in the track rails 9 and 9a, into sections designated by the reference characters a—b, b—c, c—d, d—e and e—g. Each of the sections a—b and e—g is provided with a single track circuit including a suitable source of current such, for example, as a battery 8, connected across the rails adjacent one end of the section, and a traffic responsive track relay, designated by the reference character 1TR or 5TR, respectively, connected across the rails adjacent the opposite end of the section. Each of the relays 1TR and 5TR is normally energized by current from the corresponding track battery 8, but becomes deenergized in response to a train on the corresponding section of track.

Each of the sections b—c, c—d and d—e is provided with two track circuits, one for each direction of traffic movements. I shall assume that the direction from left to right, as shown in the drawings, is eastbound, and therefore the opposite direction from right to left is westbound. Accordingly, the track circuit for eastbound traffic movements over each of the sections b—c, c—d and d—e includes a suitable source of current such, for example, as a battery 8, connected at times across the rails adjacent the east end of the section, and a traffic responsive track relay, designated by the reference character TR with a distinguishing prefix, connected at times across the rails adjacent the west end of the section. The

track circuit for the westbound traffic movements over each of the sections b—c, c—d and d—e includes one of the batteries 8 connected at times across the rails adjacent the west end of the section, and a traffic responsive track relay TR connected at times across the rails adjacent the east end of the section.

The track circuits shown for sections b—c, c—d and d—e are of the coded type. Current supplied to each of the track circuits for these sections from the corresponding track battery 8 is at times controlled by a contact 10 of a code transmitting device, designated by the reference character 75CT, and is at other times controlled by a contact 11 of a code transmitting device, designated by the reference character 180CT.

The control element of each of the code transmitters 75CT and 180CT is constantly connected across the terminals B and N of a suitable source of current such, for example, as a battery Q shown in Fig. 1b. Contact 10 of each of the code transmitters 75CT is therefore repeatedly closed and opened at a predetermined frequency such, for example, as 75 times per minute, and contact 11 of each of the code transmitters 180CT is repeatedly closed and opened at a second predetermined frequency such, for example, at 180 times per minute.

The track relays for each of the track circuits for sections b—c, c—d and d—e are of the code following type, and therefore these relays repeatedly close their contacts at their front and back points alternately at a frequency of 75 or 180 times per minute according as the control elements of these relays are energized by current of the 75 or 180 code frequency, respectively, from the corresponding track circuit.

The eastbound and westbound track circuits for each of the track sections b—c, c—d and d—e are selectively controlled by polar contacts of polar traffic control relays, each of which is designated by the reference character FR preceded by a suitable distinguishing prefix, so that only one of the track circuits is prepared at any given time for each of these track sections. The track relay for each of these track sections becomes deenergized in response to a train on the corresponding track section.

Signals designated by the reference characters RA2, RB2 and R4 govern eastbound traffic movements over the stretch of track, and a signal designated by the reference character R6 governs eastbound traffic movements leaving the stretch of track. Signals designated by the reference characters LA6, LB6 and L3 govern westbound traffic movements over the stretch of track shown, and signal L2 governs traffic movements off of the stretch of track. The signals may be of any suitable design such, for example, as the color light type, comprising a green or clear proceed lamp G, a yellow or caution proceed lamp Y, and a red or stop lamp R, as shown in the drawings.

A polar traffic control relay, designated by the reference character AFR or DFR, is provided adjacent the location of each of the pairs of signals RA2—RB2, and LA6—LB6, respectively, at opposite ends of the stretch of track, and a polar traffic control relay, designated by the reference character BFR or CFR, is provided for each of the signals L3 and R4, respectively, which govern traffic movements over the stretch of track between the pairs of signals RA2—RB2 and LA6—LB6. Relays AFR, BFR, CFR and DFR are connected in series with each other in a traffic control circuit path which extends between relays AFR and DFR.

A suitable source of current such, for example, as a battery designated by the reference character 1Q, is connected to the west end of this traffic control circuit path in opposition to a second suitable source of current of similar potential such, for example, as a battery 2Q, which is connected to the east end of this traffic control circuit path. Since the batteries 1Q and 2Q are of similar potential, but of opposite polarity, the polar traffic control relays AFR, BFR, CFR and DFR are normally not energized.

In order to prevent the passage of current over this traffic control circuit path from either of the batteries 1Q or 2Q if there should be a difference of potential between these two batteries, a first asymmetric unit, designated by the reference character 1*i*, is connected in series with battery 1Q at the west end of this traffic control circuit path, and a second asymmetric unit, designated by the reference character 2*i*, is connected in series with battery 2Q at the east end of the traffic control circuit path, with the low resistance direction of the two asymmetric units in opposition to each other. Asymmetric units 1*i* and 2*i* may be of any suitable design such, for example, as the well-known half-wave copper oxide rectifier type.

A first traffic locking relay, designated by the reference character RFL, is connected in series with battery 1Q at the west end of the traffic control circuit path referred to, and a second traffic locking relay, designated by the reference character LFL, is connected in series with battery 2Q at the east end of the traffic control circuit path. Since there is normally no current flowing between batteries 1Q and 2Q, relays RFL and LFL are normally deenergized.

First and second traffic locking repeater relays, designated by the reference characters RFLP and LFLP, respectively, are controlled by relays RFL and LFL, respectively. Each of the relays RFLP and LFLP is made slow releasing by a resistor, designated by the reference character *s*, and an energy storing device such, for example, as a capacitor, designated by the reference character *t*, connected in series with each other around the winding of each of these relays.

Operated in conjunction with switches 1 and 5 are switch circuit controller contacts designated by the reference characters 1WC and 5WC, respectively. Each of these switch circuit controller contacts is closed in a normal position, when the corresponding switch is in its normal position, as shown in Figs. 1a and 1d, and is closed in a reverse position, when the corresponding switch is in the reverse position.

A normal switch indication relay, designated by the reference character 1NWC, is controlled by contact 1WC in the normal position, and a reverse switch indication relay, designated by the reference character 1RWC, is controlled by contact 1WC in its reverse position. Normal and reverse switch indication relays 5NWC and 5RWC are similarly controlled by contact 5WC in its normal and reverse positions, respectively.

Signals L2 and R6 are controlled by means including home signal relays designated by the reference characters L2H and R6H, respectively. Relay L2H may be controlled by means including a manually operable device such, for example, as a lever L2V, and by track relay 1TR. Relay R6H may be similarly controlled by means including a manually operable device such, for example, as a lever R6V, and by track relay 5TR.

A manually controllable signal relay R2HS for signals RA2 and RB2 is shown controlled by a manually operable device such, for example, as a lever R2V, and by relays RFLP and 1TR. A manually controllable signal relay L6HS for signals LA6 and LB6 is similarly controlled by a lever L6V and by relays LFLP and 5TR.

Instead of being controlled by direct wire circuits, as shown in the accompanying drawings, relays R2HS and L6HS may be controlled by a selective code system such, for example, as that shown in Letters Patent of the United States No. 2,229,249, issued January 21, 1941, to Lloyd V. Lewis, for Remote Control Systems.

Each of the levers L2V, R2V, L6V and R6V has a normal position *n*, in which it is shown in the drawings, and has also a reverse position *f* to the left, and a reverse position *r* to the right, as shown in the drawings. Each of the levers R2V and L6V is biased toward its *n* position by suitable means which may, for example, be springs designated by the reference characters *fn* and *rn* connected between each of these levers and fixed blocks *fp* and *rp*, respectively.

A first route relay, designated by the reference character R2HSP, for signals RA2 and RB2, is controlled by the manually controllable signal relay R2HS, and by switch indication relays 1NWC and 1RWC, and also by a block repeater relay designated by the reference character RBP. A second route relay, designated by the reference character L6HSP, for signals LA6 and LB6, is similarly controlled by the manually controllable signal relay L6HS and by switch indication relays 5NWC and 5RWC, and also by a block repeater relay designated by the reference character LBP.

A normal and a reverse traffic control repeater relay, designated by the reference characters LFP and RFP, respectively, with a distinguishing prefix which is the same as that in the reference character for the corresponding polar traffic control relay, are controlled by means including a contact of the corresponding polar traffic control relay in the normal and reverse positions, respectively. Each code following track relay is in turn selectively controlled by contacts of one or both of the traffic control repeater relays for the corresponding polar traffic control relay. Each of the relays ARFP and DLFP is made slow releasing by an asymmetric unit 3*i* or 4*i*, respectively, connected across its control winding.

Each of the code following track relays, in conjunction with a decoding transformer, designated by the reference character F with a distinguishing prefix, controls a home decoding relay, designated by the reference character HR with a distinguishing prefix which is the same as that in the reference character for the corresponding code following track relay. Each of the code following track relays, in conjunction with the corresponding decoding transformer and a decoding unit, designated by the reference character 180DU, also controls a distant decoding relay, designated by the reference character D with a distinguishing prefix which is the same as that in the reference character for the corresponding code following track relay. Because of the decoding unit 180DU, each distant decoding relay becomes operated in response to energization of the corresponding track relay by coded current of only a frequency of 180 pulses per minute. Each home decoding relay, however, becomes operated in response to energization of the corresponding track relay by coded current of either 75 or 180 pulses per minute. Each home decoding relay, and each distant decoding relay, on account of being controlled by a track relay, is a traffic responsive relay, and becomes deenergized in response to deenergization of the corresponding track relay by a train.

Signal RA2 is controlled by a home signal relay, designated by the reference character RA2H, and by the traffic responsive distant decoding relay designated by the reference character R2D. Signal RB2 is controlled, similarly to signal RA2, by a home signal relay, designated by the reference character RB2H, and by the distant decoding relay designated by the reference character R2D. The circuits for lighting the lamps of signal RB2 are similar to the circuits shown for lighting the lamps of signal RA2, and are accordingly omitted from the drawings. Signals LA6 and LB6 are controlled, similarly to signals RA2 and RB2, respectively, by home signal relays designated by the reference characters LA6H and LB6H, respectively, and by the traffic responsive distant decoding relay designated by the reference character L6D.

The relays RA2H and RB2H are controlled by the switch indication relays 1NWC and 1RWC, respectively, and by route relay R2HSP and home decoding relay R2HR. Relays LA6H and LB6H are similarly controlled by switch indication relays 5NWC and 5RWC, respectively, and by route relay L6HSP and home decoding relay L6HR.

A first or eastbound traffic indication relay, designated by the reference character RFK, is controlled by relays 1TR, R2HS and R2D. By means of a resistor *sk* and an energy storing device such, for example, as a capacitor *tk*, relay RFK is made slow releasing while relay 1TR is

energized. When relay 1TR becomes deenergized, however, resistor s_k and capacitor t_k are disconnected from one of the terminals of relay RFK, and therefore do not make relay RFK slow releasing. A second or westbound traffic indication relay, designated by the reference character LFK, is controlled similarly to relay RFK.

A first or eastbound block repeater relay, designated by the reference character RBP, is controlled by relays ARFP and R2D. A second or westbound block repeater relay, designated by the reference character LBP, is controlled by relays DLFP and L6D.

A first locking stick relay, designated by the reference character RA2S, and associated with signals RA2 and RB2, is controlled by relays R2HSP, RB2H, RA2H and 1TR, and also by a time element device, shown as a relay, designated by the reference character 2TE. Time element relay 2TE is controlled by a back contact of relay RA2S, as well as by relays R2HSP, RB2H and RA2H. A second locking stick relay, designated by the reference character LA6S, associated with signals LA6 and LB6, is controlled similarly to relay RA2S.

Having described, in general, the arrangement and control of the apparatus shown by the accompanying drawings, I shall now describe, in detail, its operation.

As shown by the drawings, the contacts of the polar traffic control relays AFR, BFR, CFR and DFR are in the normal position for preparing the apparatus for controlling the signals for directing a westbound traffic movement over the stretch of track shown in the drawings; signal L3 is displaying a yellow or caution indication, and all other signals are displaying a red or stop indication; track relays 1TR and 5TR are energized, track relay L3TR is energized by coded current of the 75 code frequency, track relays R4TR and L6TR are energized by current of 180 code frequency, and track relay R2TR is deenergized; each of the switches 1 and 5 is in the normal position; each of the levers L2V, R2V, L6V and R6V is in its n position; each of the relays 1NWC, 5NWC, ALFP, BLFP, CLFP, DLFP, LSHR, R4HR, L6HR, R4D, L6D, RA2S, LA6S, LFK and LBP is energized; and each of the relays 1RWC, 5RWC, RFL, REP, RFLP, LFL, LFLP, L2H, R2HS, R2HSP, RA2H, RB2H, R2HR, R6H, L6HS, L6HSP, LA6H, LB6H, R2D, L3D, AFR, BFR, CFR, DFR, ARFP, BRFP, CRFP, DRFP, RFK, 2TE and 6TE is deenergized.

In Fig. 1a, red lamp R of signal RA2 is shown lighted by a circuit passing from terminal B, through the back point of contact 161 of relay RA2H, and lamp R to terminal N. Red lamp R of signal L2 is lighted by a circuit passing from terminal B, through the back point of contact 109 of relay L2H, and lamp R of signal L2, to terminal N.

Relay 1NWC is energized by a circuit passing from terminal B, through switch circuit controller contact 1WC in its normal position, and the winding of relay 1NWC to terminal N. Relay 5NWC is shown energized in Fig. 1d for a circuit which is similar to the circuit just described for relay 1NWC.

Relay ALFP, shown in Fig. 1a is energized by a stick circuit passing from terminal B, through contact 12 of relay AFR closed in the normal position, contact 13 of relay ARFP, contact 14 of relay ALFP, and the winding of relay ALFP to terminal N. Relay ALFP will remain energized by this stick circuit until contact 12 of relay AFR becomes operated to the reverse position in response to energization of relay AFR by current of reverse polarity.

Relay BLFP, shown in Fig. 1b, is energized by a circuit passing from terminal B, through contact 16 of relay BFR closed in the normal position, contact 17 of relay BRFP, and the winding of relay BLFP to terminal N. Relay CLFP, shown in Fig. 1c, is energized by a circuit which is similar to the circuit just described for relay BLFP. Relay DLFP, shown in Fig. 1d, is energized by a circuit passing from terminal B, through contact 20 of relay DFR closed in the normal position, contact 21 of relay DRFP,

and the winding of relay DLFP in multiple with asymmetric unit 4i to terminal N.

Relay RA2S, shown in Fig. 1a, is energized by a stick circuit passing from terminal B, through contacts 22, 23 and 24 of relays R2HSP, RB2H and RA2H, respectively, front point of contact 25 of relay RA2S, and the winding of relay RA2S to terminal N.

Relay LA6S, shown in Fig. 1d, is energized by a similar stick circuit passing from terminal B, through contacts 28, 29 and 30 of relays L6HSP, LB6H and LA6H, respectively, front point of contact 31 of relay LA6S, and the winding of relay LA6S to terminal N.

Track relay L3TR, shown in Fig. 1b is energized by a circuit passing from battery 8 adjacent code transmitter 75CT, shown in Fig. 1a, through contact 10 of this code transmitter 75CT, back point of contact 34 of relay L2H, contact 35 of relay ALFP, back point of contact 36 of relay ARFP, conductor 37, rail 9 of track section $b-c$, front point of contact 38 of relay BLFP, shown in Fig. 1b, winding of relay L3TR, front point of contact 39 of relay BLFP, rail 9a of track section $b-c$, conductor 40, and the back point of contact 41 of relay ARFP, back to battery 8. With relay L3TR thus energized by current of 75 code frequency, its contacts 42 and 43 are repeatedly closing at their front and back points alternately at a frequency of 75 times per minute.

Current therefore passes from terminal B, through the front point of contact 42 of relay L3TR, and in a given direction through the central portion of primary winding m of transformer 3F to terminal N, while contact 42 is closed at its front point, and then while contact 42 is closed at its back point, current passes from terminal B, through the back point of contact 42, lower portion of primary winding m of transformer 3F, in the opposite direction, to terminal N. Alternating current is thereby generated in secondary winding y of transformer 3F, and is rectified by contact 43 of relay L3TR for energizing relay L3HR. Current of the 75 code frequency cannot pass through the adjacent decoding unit 180DU, and therefore relay L3D remains deenergized.

With relays L3HR and BLFP energized, and relay L3D deenergized, lamp Y of signal L3 is lighted by a circuit passing from terminal B, through the front point of contact 104 of relay L3HR, front point of contact 105 of relay BLFP, back point of contact 106 of relay L3D, and lamp Y of signal L3 to terminal N.

Relay R4TR, shown in Fig. 1c, is energized by current of 180 code frequency, passing from battery 8 shown adjacent code transmitter 180CT in Fig. 1b, through contact 11 of code transmitter 180CT, back point of contact 44 of relay BRFP, front point of contact 45 of relay L3HR, front point of contact 46 of relay BLFP, rail 9 of section $c-d$, front point of contact 47 of relay CLFP, winding of relay R4TR, front point of contact 48 of relay CLFP, rail 9a of section $c-d$, and front point of contact 49 of relay BLFP, back to battery 8.

With relay R4TR thus energized by coded current, relay R4HR is energized similarly to relay L3HR, as previously described. With relay R4TR energized by current of 180 code frequency, the corresponding decoding unit 180DU permits relay R4D to also be energized. Although relays R4HR and R4D are both energized, relay CRFP is deenergized, and therefore red lamp R of signal R4 is lighted by a circuit passing from terminal B, through the front point of contact 137 of relay R4HR, back point of contact 138 of relay CRFP, and lamp R of signal R4 to terminal N.

Relay L6TR, shown in Fig. 1d, is energized by current passing from battery 8 shown adjacent the code transmitter 180CT in Fig. 1c, through contact 11 of code transmitter 180CT, front point of contact 52 of relay R4D, front point of contact 53 of relay CLFP, front point of contact 54 of relay R4HR, front point of contact 55 of relay CLFP, rail 9 of section $d-e$, front point of contact 56 of relay DLFP, the winding of relay L6TR, front point

of contact 57 of relay DLFP, rail 9a of section d—e, and front point of contact 58 of relay CLFP, back to battery 8.

With relay L6TR thus energized by current of the 180 code frequency, primary winding m of transformer 6F is energized by a circuit passing from terminal B, through contact 59 of relay DFR, and contact 60 of relay L6TR closed alternately at its front and back points, to terminal N. Relay L6HR will therefore be energized similarly to relay L3HR, previously described. Relay L6D will also be energized.

With relays DLFP and L6D energized, relay LBP, shown in Fig. 1d, is energized by its pickup circuit passing from terminal B, through contacts 68 and 69 of relays DLFP and L6D, respectively, and the winding of relay LBP to terminal N. A stick circuit for relay LBP is also closed, which is the same as the pickup circuit just traced, except that it includes contact 70 of relay LBP instead of contact 69 of relay L6D.

Relay LFK is energized by a pickup circuit passing from terminal B, through contact 62 of relay L6D, back point of contact 63 of relay L6HS, contact 66 of relay 5TR, and the winding of relay LFK to terminal N. A resistor s_k and a capacitor t_k are connected in multiple with the winding of relay LFK by a path which includes the front point of contact 67 of relay 5TR.

Red lamp R of signal LA6 is lighted by a circuit passing from terminal B, through the back point of contact 101 of relay LA6H, and lamp R of signal LA6 to terminal N. Lamp R of signal R6 is lighted by a circuit passing from terminal B, through the back point of contact 163 of relay R6H, and lamp R of signal R6 to terminal N.

I shall assume that, with the various parts of the apparatus in the condition just described, a train is to move in the westbound direction over the stretch of track X shown in the accompanying drawings. A leverman or a dispatcher will therefore move lever L6V to its f position for effecting energization of relay L6HS by its pickup circuit which passes from terminal B, through contact 71 of lever L6V closed in the f position, contact 72 of relay LFLP, and the winding of relay L6HS to terminal N. Relay L6HS, upon becoming energized, completes a stick circuit passing from terminal B, through contact 73 of lever L6V, which is closed by lever L6V in its n or its f position or at any point between these two positions, contact 74 of relay 5TR, contact 75 of relay L6HS, and the winding of relay L6HS to terminal N. Since lever L6V is biased to its n position, as previously described, it will return to that position as soon as it is released by the leverman or dispatcher. Contact 71 of lever L6V will therefore open the pickup circuit traced for relay L6HS, which will, however, remain energized by its stick circuit.

With relay L6HS energized, a circuit will be completed for energizing polar traffic control relays AFR, BFR, CFR and DFR by current of normal polarity, this circuit passing from battery 1Q, shown in Fig. 1a, through contact 76 of relay 1TR, winding of relay RFL, contact 77 of relay RA2S, asymmetric unit 1i, back point of contact 78 of relay R2HS, front point of contact 79 of relay ALFP, winding of relay AFR, conductor 80, winding of relay BFR, conductor 81, winding of relay CFR, conductor 82, winding of relay DFR, back point of contact 83 of relay DRFP, front point of contact 84 of relay LFK, front point of contact 85 of relay L6HS, jumper 86, front point of contact 87 of relay L6HS, front point of contact 88 of relay LFK, back point of contact 89 of relay DRFP, conductor 90, front point of contact 91 of relay ALFP, and the back point of contact 92 of relay R2HS to terminal 1N of battery 1Q. The contacts of the polar traffic control relays AFR, BFR, CFR and DFR are already in the normal position, and will therefore not be moved in response to energization of these relays by current of normal polarity.

The westbound track circuits will therefore remain set up as previously prepared when the contacts of relays

AFR, BFR, CFR and DFR were previously moved to the normal position, as shown in the accompanying drawings.

The route relay L6HSP will, however, now be energized by a circuit passing from terminal B, through contacts 93 and 94 of relays LBP and L6HS, respectively, front point of contact 95 of relay 5NWC, back point of contact 96 of relay 5RWC, and the winding of relay L6HSP to terminal N. Relay L6HSP, upon becoming energized, opens its contact 28, thereby deenergizing relay LA6S. Relay L6HSP, however, upon becoming energized, completes a circuit for energizing relay LA6H, this circuit passing from terminal B, through contacts 97, 98, 99 and 100 of relays L6HR, 5TR, L6HSP and 5NWC, respectively, and the winding of relay LA6H to terminal N.

Relay LA6H, upon becoming energized, picks up its contact 30, and thereby opens the circuit for relay LA6S at a second point. With relays LA6H and L6D energized, green lamp G of signal LA6 will be lighted by a circuit passing from terminal B, through the front point of contact 101 of relay LA6H, front point of contact 102 of relay L6D, and lamp G of signal LA6 to terminal N.

The pickup circuit for relay LFK, previously traced through contact 62 of relay L6D, will now be opened at the back point of contact 63 of relay L6HS, but a second pickup circuit will be completed for relay LFK, which is the same as the pickup circuit previously traced except that it includes the front point of contact 63 of relay L6HS instead of contact 62 of relay L6D and the back point of contact 63 of relay L6HS.

With current now supplied from battery 1Q through the winding of traffic locking relay RFL to the traffic control circuit, relay RFL will be energized, and therefore traffic locking repeater relay RLFP will also be energized, by a circuit passing from terminal B, through contact 103 of relay RFL, and the winding of relay RLFP in multiple with a resistor s and a capacitor t , to terminal N.

Relay RLFP, upon becoming energized, opens its contact 111 in the pickup circuit for relay R2HS. Therefore, as long as the traffic control circuit is energized by current from battery 1Q passing through the winding of relay RFL, relay R2HS cannot be energized for arranging the apparatus for controlling an eastbound traffic movement over the stretch of track.

If, now, the leverman or dispatcher should decide to hold the westbound train at signal LA6, he will move lever L6V to its r position, thereby opening its contact 73 in the stick circuit for relay L6HS, and causing relay L6HS to be deenergized. With relay L6HS deenergized, relay L6HSP will, in turn, be deenergized, which will cause relay LA6H to also be deenergized.

With relay LA6H deenergized, lamp G of signal LA6 will become extinguished, and lamp R of this signal will again be lighted, as previously described. With relays L6HSP and LA6H now deenergized, time element relay 6TE will be energized by a circuit passing from terminal B, through contacts 28, 29 and 30 of relays L6HSP, LB6H and LA6H, respectively, back point of contact 31 of relay LA6S, and the winding of relay 6TE to terminal N.

Relay LA6S cannot become energized until a pickup circuit is completed for this relay by relay 6TE upon the lapse of a predetermined period of time. Therefore, a circuit for energizing the polar traffic control relays by current of reverse polarity passing from battery 2Q, through contact 116 of relay LA6S, could not at once be completed, if an attempt were made to do so by effecting energization of relay R2HS.

If, before relay 6TE has closed its contact 32 in a pickup circuit for effecting energization of relay LA6S, the westbound train has entered section e—g, relay LFK will be deenergized at contact 66 of relay 5TR, and then the circuit for energizing relays AFR, BFR, CFR and DFR by current of reverse polarity could not be completed, because contacts 84 and 88 of relay LFK

would be open at their front point. Relay LA6S would, however, then be energized by a pickup circuit passing from terminal B, through contacts 28, 29 and 30 of relays L6HSP, LB6H, and LA6H, respectively, contact 33 of relay 5TR, and the winding of relay LA6S to terminal N.

If, however, the westbound train does not enter section e—g, a second pickup circuit for relay LA6S will be completed by relay 6TE, upon the lapse of a predetermined period of time, this circuit being the same as the pickup circuit previously traced for relay LA6S except that it includes contact 32 of relay 6TE instead of contact 33 of relay 5TR. Either the circuit previously traced for energizing relays AFR, BFR, CFR and DFR by current of normal polarity, or a circuit for energizing these relays by current of reverse polarity, could then be completed.

I shall assume that the leverman or dispatcher now again effects energization of the polar traffic control relays by current of normal polarity and the lighting of lamp G of signal LA6 by moving lever L6V to its f position for energizing relay L6HS. A westbound train, upon entering section e—g, deenergizes relay 5TR, so that contact 66 of relay 5TR opens the circuit for relay LFK, as previously described.

Contact 67 of relay 5TR also opens the path through resistor sk and capacitor tk which is in multiple with the winding of relay LFK, and therefore relay LFK will release quickly. Contact 67 of relay 5TR, upon becoming closed at its back point, completes a circuit for discharging capacitor tk, this circuit passing from capacitor tk, through resistor sk, and back point of contact 67 of relay 5TR, back to capacitor tk.

Relay 5TR, upon becoming deenergized, also opens, at its contact 74, the stick circuit for relay L6HS, causing relay L6HS to become deenergized, which in turn causes relays L6HSP and LA6H to be deenergized. Relay LA6S will now become energized by its first pickup circuit, previously traced, which includes contact 33 of relay 5TR. With relay LA6H deenergized, lamp R of signal LA6 will again be lighted.

With relay LFK deenergized, relays AFR, BFR, CFR and DFR will be retained energized by current of normal polarity, although relay L6HS is deenergized. The circuit for retaining the polar traffic control relays energized by current of normal polarity is the same as the circuit previously traced for energizing these relays by current of normal polarity except that it includes the back points of contacts 84 and 88 of relay LFK instead of the front points of these contacts and the front points of contacts 85 and 87 of relay L6HS.

When the train enters section d—e, relay L6TR will be deenergized, causing relays L6HR and L6D to also be deenergized. The pickup circuit for relay LBP will now be open at contact 69 of relay L6D, but relay LBP will be retained energized by its stick circuit previously traced, which will remain closed until relay DFR becomes energized by current of reverse polarity and thereby deenergizes relay DLFP, causing contact 68 of relay DLFP to be opened.

When the train leaves section e—g, relay 5TR will again become energized. Relay LFK will, however, remain deenergized, because contact 62 of relay L6D will still be open.

When the train enters section c—d, relay R4TR will become deenergized, causing relays R4HR and R4D to also be deenergized.

When the train leaves section d—e, relays R4HR and R4D will remain deenergized while relay R4TR remains deenergized because of the train occupying section c—d. On account of relay CRFP being deenergized, its contact 164 will be open, and therefore current of the 75 code frequently cannot be supplied to section d—e through the back point of contact 54 of relay R4HR. Relay L6TR will therefore remain deenergized while sec-

tion c—d is occupied, although section d—e is unoccupied.

When the train enters section b—c, relay L3TR will become deenergized, causing relay L3HR to also, in turn, become deenergized. Relay L3HR, upon becoming deenergized, extinguishes lamp Y of signal L3, and completes a circuit for energizing lamp R of signal L3, this circuit passing from terminal B, through the back point of contact 104 of relay L3HR, and lamp R of signal L3 to terminal N.

On account of the polar traffic control relays remaining energized by current of normal polarity passing through the back points of contacts 84 and 88 of relay LFK while the stretch of track is occupied by a westbound train between signals LA6 and L2, the contacts of the polar traffic control relays are less likely to be misplaced in some way such, for example, as by a surge of induced current, than if the polar traffic control relays were deenergized while the stretch of track is occupied. If, however, the contacts of any of the polar traffic control relays AFR, BFR, CFR and DFR should become misplaced because of the corresponding relay becoming energized by induced current of reverse polarity due to a surge of current while track X is occupied by a westbound train between signals LA6 and L2, such misplaced contacts would be restored to the normal position as soon as the surge of induced current ended.

When the train leaves section c—d, relay R4TR will become energized by current of the 75 code frequency passing from battery 8 at signal L3, through contact 10 of code transmitter 75CT at signal L3, contact 165 of relay BLFP, back point of contact 45 of relay L3HR, front point of contact 46 of relay BLFP, rail 9 of section c—d, front point of contact 47 of relay CLFP, winding of relay R4TR, front point of contact 48 of relay CLFP, rail 9a of section c—d, and front point of contact 49 of relay BLFP, back to battery 8. With relay R4TR thus energized by coded current of the 75 code frequency, relay R4HR will become energized, as previously described, but relay R4D will remain deenergized.

Relay L6TR will then be energized by current of the 75 code frequency passing from battery 8 at signal R4, through contact 10 of code transmitter 75CT at signal R4, back point of contact 52 of relay R4D, front point of contact 53 of relay CLFP, front point of contact 54 of relay R4HR, front point of contact 55 of relay CLFP, rail 9 of section d—e, front point of contact 56 of relay DLFP, the winding of relay L6TR, front point of contact 57 of relay DLFP, rail 9a of section d—e, and the front point of contact 58 of relay CLFP, back to battery 8 at signal R4. With relay L6TR energized by current of the 75 code frequency, relay L6HR will also be energized, but relay L6D will remain deenergized.

On account of relay LBP being still energized by its stick circuit, the leverman or dispatcher could, if he so desired, now control signal LA6 to display the yellow indication for a second westbound train while the first westbound train occupies the stretch of track between signals L3 and L2. To do this, the leverman or dispatcher would move lever L6V to its f position for effecting energization of relay L6HS as previously described. Relay L6HSP, and, in turn, relay LA6H would then become energized. Relay LA6H, upon becoming energized, would open, at the back point of its contact 161, the circuit for lamp R of signal LA6, causing this lamp to be extinguished, and would then complete a circuit for lighting lamp Y, this circuit passing from terminal B, through the front point of contact 161 of relay LA6H, back point of contact 102 of relay L6D, and lamp Y of signal LA6 to terminal N.

In order to control signal L2 to display a proceed indication for the first westbound train, the leverman or dispatcher may move lever L2V to its f position, thereby completing an energizing circuit for relay L2H, this circuit passing from terminal B, through contact 107 of lever

L2V, contact 108 of relay 1TR, and the winding of relay L2H to terminal N. Contact 109 of relay L2H will then move from its back point to its front point, thereby extinguishing lamp R of signal L2 and completing a circuit for lighting lamp Y of this signal, this circuit passing from terminal B, through the front point of contact 109 of relay L2H, and lamp Y of signal L2 to terminal N.

When the first westbound train enters section *a*—*b*, relay 1TR will become deenergized, which will in turn deenergize relay L2H, causing contact 109 of relay L2H to open the circuit for lamp Y, and again complete the circuit for lamp R of signal L2, so that signal L2 will now again display a red or stop indication. When relay 1TR becomes deenergized, its contact 76 will open the circuit for relay RFL and the polar traffic control relays AFR, BFR, CFR and DFR. With relay RFL deenergized, relay RFLP will in turn be deenergized, because contact 103 of relay RFL will be open.

When the first westbound train leaves section *b*—*c*, relay L3TR will again be energized, as previously traced, by current of the 75 code frequency. Relay L3HR will then again become energized, and yellow lamp Y of signal L3 will again be lighted, as previously described.

When the stretch of track between signals LA6 and RA2 is again unoccupied, and all levers are again returned to the *n* position, all parts of the apparatus will again be in the condition shown in the drawings.

I shall now assume that an eastbound traffic movement is to be made over track X. A leverman or dispatcher will therefore move lever R2V to its *r* position, thereby completing a pickup circuit for relay R2HS passing from terminal B, through contact 110 of lever R2V, contact 111 of relay RFLP, and the winding of relay R2HS to terminal N. Relay R2HS, upon becoming energized by its pickup circuit, completes its stick circuit passing from terminal B, through contact 112 of lever R2V, contact 113 of relay 1TR, contact 114 of relay R2HS, and the winding of relay R2HS to terminal N.

Relays AFR, BFR, CFR and DFR will now be energized by current of reverse polarity supplied by battery 2Q, shown in Fig. 1d, through the winding of relay LFL, this circuit passing from battery 2Q, through contact 115 of relay 5TR, winding of relay LFL, contact 116 of relay LA6S, asymmetric unit 2*i*, back point of contact 85 of relay L6HS, front point of contact 84 of relay LFK, back point of contact 83 of relay DRFP, winding of relay DFR, conductor 82, winding of relay CFR, conductor 81, winding of relay BFR, conductor 80, winding of relay AFR, front point of contact 79 of relay ALFP, front point of contact 78 of relay R2HS, conductor 117, front point of contact 92 of relay R2HS, front point of contact 91 of relay ALFP, conductor 90, back point of contact 89 of relay DRFP, front point of contact 88 of relay LFK, and the back point of contact 87 of relay L6HS to terminal 2N of battery 2Q.

Relay R2HS, upon becoming energized, also completes a circuit for energizing relay RFK, this circuit passing from terminal B, through the front point of contact 119 of relay R2HS, contact 122 of relay 1TR, and the winding of relay RFK to terminal N. Lever R2V will be returned, by its biasing means, to its *n* position, when the leverman or dispatcher removes his hand from this lever. Relay R2HS will, however, then be retained energized by its stick circuit, previously traced.

Relay AFR, upon becoming energized by current of reverse polarity, will move its contact 12 to the righthand position, thereby deenergizing relay ALFP and completing a circuit for energizing relay ARFP, this circuit passing from terminal B, through contact 12 of relay AFR closed in the right-hand or reverse position, contact 126 of relay ALFP, and the winding of relay ARFP in multiple with an asymmetric unit 3*i* to terminal N.

Relay BFR, upon becoming energized by current of reverse polarity, will move its contact 16 from the normal position to the reverse position, thereby deenergizing

relay BLVP and completing a circuit for energizing relay BRFP, this circuit passing from terminal B, through contact 16 of relay BFR closed in the reverse position, contact 127 of relay BLFP, and the winding of relay BRFP to terminal N.

Relay CFR, upon becoming energized by current of reverse polarity, will deenergize relay CLFP and effect energization of relay CRFP similarly to the manner in which relay BFR effects deenergization of relay BLFP and energization of relay BRFP.

Relay DFR, upon becoming energized by current of reverse polarity, will move its contact 20 to the reverse position, thereby deenergizing relay DLFP.

Relay LFL, upon becoming energized by current of reverse polarity supplied to relays AFR, BFR, CFR and DFR, will close its contact 129, thereby completing a circuit for energizing relay LFLP, this circuit passing from terminal B, through contact 129 of relay LFL, and the winding of relay LFL in multiple with a resistor *s* and a capacitor *t* to terminal N.

A circuit will therefore now be completed for energizing relay DRFP, this circuit passing from terminal B, through contact 20 of relay DFR closed in the reverse position, contact 130 of relay DLFP, contact 131 of relay LFLP, and the winding of relay DRFP to terminal N. Relay DRFP, upon becoming energized by its pickup circuit just traced, will complete a stick circuit which is the same as the pickup circuit, just traced, except that it includes contact 132 of relay DRFP instead of contact 131 of relay LFLP.

The purpose of including a front contact of relay LFLP in the pickup circuit for relay DRFP is to insure that the contacts of relay LFLP are operated to the energized position before current can be supplied through contact 134 of relay DRFP to the eastbound track circuit for section *d*—*e*.

With relay RFK energized and relay ALFP deenergized, the circuit for energizing relays AFR, BFR, CFR and DFR by current of reverse polarity will now include the back point of contact 79 of relay ALFP in series with the front point of contact 124 of relay RFK, and the back point of contact 91 of relay ALFP in series with the front point of contact 125 of relay RFK, instead of including the front points of contacts 79 and 91 of relay ALFP as previously traced.

With relay LFLP energized, its contact 72 will be open in the pickup circuit for relay L6HS, so that it will be impossible for a leverman or dispatcher to effect energization of relay L6HS for a westbound traffic movement while the traffic control relays are energized by current of reverse polarity for an eastbound traffic movement.

With relay DRFP energized, the circuit for energizing the polar traffic control relays by current of reverse polarity will now include the frontpoint of contacts 83 and 89 of relay DRFP instead of the back points of these contacts and the front points of contacts 84 and 88 of relay LFK.

With relay DFR energized by current of reverse polarity, its contact 59 will be open, and therefore relays L6HR and L6D will be deenergized. With relay DLFP deenergized, relay LBP will also be deenergized by the opening of contact 68 of relay DLFP.

Relay R4TR will now be energized by current of the 75 code frequency passing from battery 3 adjacent code transmitter 75CT, shown in Fig. 1d, through contact 10 of this code transmitter 75CT, back point of contact 133 of relay R6H, contact 134 of relay DRFP, back point of contact 56 of relay DLFP, rail 9 of section *d*—*e*, back point of contact 55 of relay CLFP, contact 135 of relay CRFP, winding of relay R4TR, contact 136 of relay CRFP, back point of contact 58 of relay CLFP, rail 9a of section *d*—*e*, and the back point of contact 57 of relay DLFP, back to battery 8. With relay R4TR energized by current of the 75 code frequency, relay R4HR will be

energized, but relay R4D will be deenergized. With relay R4HR energized and relay R4D deenergized, lamp Y of signal R4 will be lighted by a circuit passing from terminal B, through the front point of contact 137 of relay R4HR, front point of contact 138 of relay CRFP, back point of contact 139 of relay R4D, and lamp Y of signal R4 to terminal N.

Relay L3TR will now be energized by current of the 180 code frequency in a circuit passing from battery 8 adjacent signal R4, through contact 11 of code transmitter 180CT adjacent signal R4, back point of contact 53 of relay CLFP, front point of contact 54 of relay R4HR, contact 140 of relay CRFP, back point of contact 48 of relay CLFP, rail 9a of section c—d, back point of contact 49 of relay BLFP, contact 141 of relay BRFP, winding of relay L3TR, contact 142 of relay BRFP, back point of contact 46 of relay BLFP, rail 9 of section c—d, back point of contact 47 of relay CLFP, and contact 143 of relay CRFP, back to battery 8. With relay L3TR now energized by current of the 180 code frequency, relays L3HR and L3D will be energized, on account of being controlled by contacts 42 and 43 of relay L3TR. With relay BLFP deenergized, lamp Y of signal L3 will be extinguished, and lamp R of signal L3 will be lighted by a circuit passing from terminal B, through the front point of contact 104 of relay L3HR, back point of contact 105 of relay BLFP, and lamp R of signal L3 to terminal N.

Relay R2TR will now be energized by current of the 180 code frequency passing from battery 8 at signal L3, through contact 11 of code transmitter 180CT at signal L3, front point of contact 144 of relay L3D, front point of contact 44 of relay BRFP, front point of contact 45 of relay L3HR, contact 145 of relay BRFP, back point of contact 39 of relay BLFP, rail 9a of section b—c, conductor 40, front point of contact 41 of relay ARFP, winding of relay R2TR, front point of contact 36 of relay ARFP, conductor 37, rail 9 of section b—c, back point of contact 38 of relay BLFP, and contact 146 of relay BRFP, back to battery 8. With relay R2TR energized by current of the 180 code frequency, relays R2HR and R2D will be energized by circuits controlled by contact 147 of relay AFR and the front and back points of contacts 148 and 149 of relay R2TR.

With relay R2D now energized, relay RBP will become energized by its pickup circuit passing from terminal B, through contacts 150 and 151 of relays ARFP and R2D, respectively, and the winding of relay RBP to terminal N. Relay RBP, upon becoming energized, completes a stick circuit which is the same as the pickup circuit just traced except that it includes contact 152 of relay RBP instead of contact 151 of relay R2D.

Relay RBP, upon becoming energized, completes a circuit for energizing relay R2HSP, this circuit passing from terminal B, through contacts 153 and 154 of relays RBP and R2HS, respectively, front point of contact 155 of relay INWC, back point of contact 156 of relay 1RWC, and the winding of relay R2HSP to terminal N. Relay RA2H will then become energized by a circuit passing from terminal B, through contact 157 of relay R2HR, contact 158 of relay 1TR, contact 159 of relay R2HSP, contact 160 of relay INWC, and the winding of relay RA2H to terminal N. With relays RA2H and R2D energized, lamp G of signal RA2 will now be lighted by a circuit passing from terminal B, through the front point of contact 161 of relay RA2H, front point of contact 162 of relay R2D, and lamp G of signal RA2 to terminal N.

Relay R2HSP, upon becoming energized, opens its contact 22, thereby deenergizing relay RA2S. When an eastbound train enters section a—b, contact 113 of relay 1TR will open the stick circuit for relay R2HS, causing relay R2HS to become deenergized. Relay RFK will also be deenergized by contact 122 of relay 1TR. Relays AFR, BFR, CFR and DFR will then be retained energized by current of reverse polarity in a

circuit which is the same as the circuit previously traced for energizing these relays by current of reverse polarity except that it now includes the back points of contacts 79 and 91 of relay ALFP and the back points of contacts 124 and 125 of relay RFK instead of the front points of contacts 79 and 91 of relay ALFP and the front points of contacts 78 and 92 of relay R2HS. The operation of the apparatus as the eastbound train now moves over the stretch of track between signals RA2 and LA6 will be similar to the operation of the apparatus already described when a westbound train moves over the stretch of track between signals LA6 and RA2.

From the foregoing description of the operation of the apparatus, it follows that, in apparatus embodying my invention, all of the polar traffic control relays are retained energized by current of normal polarity or all of the polar traffic control relays are retained energized by current of reverse polarity while a westbound or an eastbound train, respectively, is moving over the corresponding stretch of track.

I shall next assume that the various parts of the apparatus are again in the condition shown in the drawings, that is, that the polar traffic control relays are deenergized and the contacts of these relays are closed in the normal position, for example, as shown, and that the stretch of track is unoccupied between signals RA2 and LA6, and also that relays R2HS and L6HS are in the deenergized condition. I shall assume further that, with the parts of the apparatus in that condition, an induced surge of current energizes only relay BFR in the reverse direction, causing contact 16 of relay BFR to be moved to the reverse position. Relay BLFP will therefore be deenergized, and relay BRFP will become energized, as previously described.

Battery 8, at signal L3, will therefore be disconnected from section c—d, and therefore relay R4TR will be deenergized. With relay R4TR deenergized, relays R4HR and R4D will also be deenergized, causing battery 8 at signal R4 to be disconnected from section d—e.

Relay L6TR will then be deenergized, causing relays L6HR and L6D to also be deenergized.

With relay L6D deenergized, relay LFK will become deenergized, thereby constituting auxiliary means for effecting energization of the polar traffic control relays by current of normal polarity in the circuit previously described. The polar contact 16 of relay BFR will therefore be restored to the normal position, causing relay BRFP to again be deenergized and causing relay BLFP to again become energized. Relays R4TR, R4HR, R4D, L6TR, L6HR and L6D will then in turn again become energized.

With relay L6D again energized, relay LFK will also again be energized, thereby opening the auxiliary circuit path for supplying current of normal polarity to the polar traffic control relays AFR, BFR, CFR and DFR. All parts of the apparatus will then again be in the condition shown in the drawings.

I shall now assume that, with all parts of the apparatus again in the condition shown in the drawings, relay AFR becomes energized in the reverse direction by an induced surge of current which causes the contacts of relay AFR to be moved to the reverse position. Relay ALFP will then serve as auxiliary means for effecting energization of the polar traffic control relays AFR, BFR, CFR and DFR by current of reverse polarity through the back points of contacts 79 and 91 of relay ALFP and the back points of contacts 124 and 125 of relay RFK.

The contacts of the relays BFR, CFR and DFR also will next be moved to the reverse position. The track circuits will then be set up for an eastbound traffic movement, as previously described when relay R2HS became energized. When relay R2D becomes energized, relay RFK will become energized by a circuit passing from terminal B, through contact 118 of relay R2D, back

point of contact 119 of relay R2HS, contact 122 of relay 1TR, and the winding of relay RFK to terminal N.

With relay RFK energized, the auxiliary path through the back points of contacts 79 and 91 of this relay for effecting energization of relays AFR, BFR, CFR and DFR by current of reverse polarity will be opened, and the contacts of all of the relays AFR, BFR, CFR and DFR will remain closed in the reverse position. The apparatus will thus be prepared for an eastbound traffic movement similarly to the arrangement of the apparatus shown in the drawings for a westbound traffic movement.

From the foregoing description of the operation of the apparatus, it follows that apparatus embodying my invention is self-restoring, that is, if any one of the polar traffic control relays AFR, BFR, CFR and DFR becomes operated, such for example as by a surge of induced current, all the polar traffic control relays will become energized by current of one polarity which may be either normal or reverse, so that the polar contacts of all the polar traffic control relays will be placed in either the normal position, or all will be placed in the reverse position.

I shall next assume that all parts of the apparatus are again in the condition shown in the drawings, and that, in some way, relays ALFP and LFK become deenergized while relays RFK and DRFP are also deenergized. The polar traffic control relays AFR, BFR, CFR and DFR will therefore be in series in a closed circuit path which includes the back points of contacts 79 and 91 of relay 30 ALFP, the back points of contacts 124 and 125 of relay RFK, the back points of contacts 83 and 89 of relay DRFP, and the back points of contacts 84 and 88 of relay LFK. This closed circuit path is without any source of current, and therefore the apparatus is in a locked-out or inoperative condition.

With relay ALFP deenergized, battery 8, shown adjacent code transmitter 75CT in Fig. 1a, will be disconnected from section b—c, and with relay DRFP deenergized, battery 8, shown adjacent code transmitter 75CT in Fig. 1d, will remain disconnected from section d—e. With battery 8 shown adjacent code transmitter 75CT in Fig. 1a disconnected from section b—c, relay L3TR will be deenergized. Current of the 75 code frequency will therefore be supplied from battery 8 at signal L3 to section c—d, and therefore relay L6D, shown in Fig. 1d, will be deenergized.

In order to restore the apparatus to an operative condition, a leverman or dispatcher will manually effect energization of one of the manually controllable signal relays R2HS or L6HS. If, for example, a leverman or dispatcher should effect energization of relay R2HS, as previously described, relay RFK would become energized by its pickup circuit previously traced through the front point of contact 119 of relay R2HS.

Since block repeater relay RBP is not energized, route relay R2HSP will not become energized when the leverman or dispatcher effects energization of relay R2HS. Since relay R2HSP does not become energized, relay RA2S will not become deenergized, and therefore the stick locking will not become effective. Also, since relay R2HSP does not become energized, relay RA2H will not become energized, and therefore signal RA2 will continue to display the red or stop indication.

The leverman or dispatcher will not deenergize relay R2HS by moving lever R2V to its f position and thereby opening its contact 112 in the stick circuit for relay R2HS. Contact 119 of relay R2HS will then become opened at its front point, thereby deenergizing relay RFK.

Relay RFK, however, as already pointed out, is slow releasing if its circuit becomes opened while relay 1TR is energized. Relay RFK will therefore retain its contacts 124 and 125 closed at the front points in a circuit for energizing relay RFL in series with relays AFR, BFR, CFR and DFR by current of normal polarity, until after

relay RFL has closed its front contact 103 and relay RFLP has in turn become energized. Relay RFLP, upon becoming energized, closes its contact 120 in a stick circuit for retaining relay RFK energized, this stick circuit passing from terminal B, through contact 120 of relay RFLP, contact 121 of relay RFK, contact 122 of relay 1TR, and the winding of relay RFK in multiple with the path which includes resistor sk and capacitor tk to terminal N.

When contact 12 of relay AFR becomes closed in the normal position, relay ALFP will become energized by its pickup circuit passing from terminal B, through contact 12 of relay AFR closed in the normal position, contact 13 of relay ARFP, contact 15 of relay RFLP, and the winding of relay ALFP to terminal N. With contact 35 of relay ALFP now closed, the track circuits for a westbound traffic movement will be set up as previously described.

Relay LFK will then again become energized by its pickup circuit previously traced, which includes contact 62 of relay L6D. Relay LFK, upon becoming energized, will open its contacts 84 and 88 at their back points, thereby opening the circuit previously described for energizing the polar traffic control relays by current of normal polarity.

With this circuit again opened, relay RFL will become deenergized, and in turn relay RFLP will be deenergized. Relay RFLP, upon becoming deenergized, opens its contact 120 in the stick circuit for relay RFK, causing relay RFK to also again be deenergized.

It follows that my invention provides an arrangement by which a leverman or dispatcher can restore the apparatus to an operative condition in the event of a locked-out or inoperative condition caused by some unusual occurrence.

It will be noted that, by means of the block repeater relays RBP and LBF, a check of the system is provided after each traffic control reversal. The pickup circuit for relay RBP, for example, is controlled by front contacts of relays ARFP and R2D. Before relay RBP can become energized after the traffic control apparatus has been changed from westbound control to eastbound control, each of the traffic control relays AFR, BFR, CFR and DFR must have closed its polar contacts in the reverse position, and then the track circuit apparatus must have been prepared for an eastbound traffic movement in response to the closing of the contacts of relays AFR, BFR, CFR and DFR in the reverse position, and the stretch of track must be unoccupied. Relay RBP will then remain energized until the traffic control apparatus is again changed back to the condition shown in the drawings for controlling westbound traffic.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway traffic controlling apparatus for a stretch of railway track which is provided with a plurality of signals for governing traffic movements in a first direction and in the opposite or second direction over said stretch of railway track, embodying a plurality of polar traffic control relays one for each of said signals connected in series in a traffic control circuit, each of said relays having polar contacts which when the corresponding relay becomes deenergized remain closed in the normal or reverse position to which they were last operated in response to current of normal or reverse polarity respectively, the combination comprising, first manually controllable signal control means having a normal condition and manually operable to a second condition, second manually controllable signal control means having a normal condition and manually operable to a second condition, a first traffic locking relay, a second traffic locking relay, means controlled by said first man-

ually controllable means in its normal condition and by said second manually controllable means in its second condition for supplying current of a given or normal polarity to said traffic control circuit through the winding of said first traffic locking relay, means controlled by said first manually controllable means in its second condition and by said second manually controllable means in its normal condition for supplying current of the opposite or reverse polarity to said traffic control circuit through the winding of said second traffic locking relay, a first traffic indication relay, a second traffic indication relay, a first traffic responsive relay energized by means controlled by contacts of said traffic control relays in the reverse position but becoming deenergized in response to a train entering said stretch in said first direction, a second traffic responsive relay energized by means controlled by contacts of said traffic control relays in the normal position but becoming deenergized in response to a train entering said stretch in said second direction, means controlled by either said first manually controllable means in its second condition or by said first traffic responsive relay in the energized condition for energizing said first traffic indication relay, means controlled by either said second manually controllable means in its second condition or by said second traffic responsive relay in the energized condition for energizing said second traffic indication relay, means controlled by said first traffic locking relay in the energized condition for retaining said first traffic indication relay energized, means controlled by said second traffic locking relay in the energized condition for retaining said second traffic indication relay energized, means including back contacts of said first or second traffic indication relay for energizing said traffic control circuit by current of reverse or normal polarity respectively in response to a train entering said stretch of track, means including contacts of the corresponding traffic control relays closed in the normal position for controlling said signals for governing traffic movements in the second direction, and means including contacts of the corresponding traffic control relays closed in the reverse position for controlling said signals for governing traffic movements in the first direction.

2. In railway traffic controlling apparatus for a stretch of railway track which is provided with a plurality of signals for governing traffic movements in a first direction and in the opposite or second direction over said stretch of railway track, embodying a plurality of polar traffic control relays one for each of said signals connected in series in a traffic control circuit, each of said relays having polar contacts which when the corresponding relay becomes deenergized remain closed in the normal or the reverse position to which they were last operated in response to current of normal or reverse polarity respectively, the combination comprising, first manually controllable signal control means having a normal condition and manually operable to a second condition, second manually controllable signal control means having a normal condition and manually operable to a second condition, a first traffic locking relay, a second traffic locking relay, means controlled by said first manually controllable means in its normal condition and by said second manually controllable means in its second condition for supplying current of a given or normal polarity to said traffic control circuit through the winding of said first traffic locking relay, means controlled by said first manually controllable means in its second condition and by said second manually controllable means in its normal condition for supplying current of the opposite or reverse polarity to said traffic control circuit through the winding of said second traffic locking relay, a first traffic indication relay, a second traffic indication relay, a first traffic responsive relay energized by means controlled by contacts of said traffic control relays in the reverse position but becoming deenergized in response to a train entering said stretch in said first direction

tion, a second traffic responsive relay energized by means controlled by contacts of said traffic control relays in the normal position but becoming deenergized in response to a train entering said stretch in said second direction, means controlled by said first traffic responsive relay in the energized condition for energizing said first traffic indication relay, means controlled by said second traffic responsive relay in the energized condition for energizing said second traffic indication relay, means controlled by said first traffic locking relay in the energized condition for retaining said first traffic indication relay energized, means controlled by said second traffic locking relay in the energized condition for retaining said second traffic indication relay energized, means including said first or second traffic indication relay in the deenergized condition for energizing said traffic control circuit by current of reverse or normal polarity respectively in response to a train entering said stretch of track, and means including the corresponding polar traffic control relays for controlling said signals.

3. In combination, a stretch of railway track, a plurality of signals for governing traffic movements in a given first direction and in the opposite or second direction over said stretch of railway track, a plurality of polar traffic control relays one for each of said signals connected in series, each of said relays having polar contacts which when the corresponding relay becomes deenergized remain closed in the normal or the reverse position to which they were last previously operated in response to current of normal or reverse polarity respectively, first manually controllable means and second manually controllable means each having a normal condition and each manually operable to a second condition, a first traffic locking relay, a second traffic locking relay, means controlled by said first manually controllable means in its normal condition and by said second manually controllable means in its second condition for supplying current of a given normal polarity for energizing said first traffic locking relay and said polar traffic control relays all in series, means controlled by said first manually controllable means in its second condition and by said second manually controllable means in its normal condition for supplying current of the opposite or reverse polarity for energizing said second traffic locking relay and said polar traffic control relays all in series, a first traffic indication relay, a second traffic indication relay, a first traffic responsive relay energized by means controlled by contacts of said traffic control relays in the reverse position, a second traffic responsive relay energized by means controlled by contacts of said traffic control relays in the normal position, each of said first and second traffic responsive relays becoming deenergized in response to a train moving on said stretch of track in said first or said second directions respectively, means controlled by said first traffic responsive relay in the energized condition for energizing said first traffic indication relay, means controlled by said second traffic responsive relay in the energized condition for energizing said second traffic indication relay, means controlled by said first or second traffic locking relay in the energized condition for retaining said first or second traffic indication relay respectively energized, means including back contacts of said first or second traffic indication relay for energizing said second or first traffic locking relays respectively by current of reverse or normal polarity respectively in series with said polar traffic control relays in response to a train on said stretch of track, and means including said traffic responsive relays for controlling said signals.

4. In combination, a stretch of railway track divided into a first portion adjacent a given first end of said stretch, a second portion adjacent the opposite or second end of said stretch and an intermediate third portion between said first and said second portions, a first and a second signal adjacent the first and second ends respectively of said stretch for governing traffic movements in

opposite directions onto said stretch, a first and a second polar traffic control relay each having polar contacts which when the corresponding relay becomes deenergized remain closed in the normal or the reverse position to which they were last previously operated in response to current of normal or reverse polarity respectively, a first traffic responsive relay energized by means controlled by contacts of said traffic control relays in the reverse position, a second traffic responsive relay energized by means controlled by contacts of said traffic control relays in the normal position, each of said first and said second traffic responsive relays becoming deenergized in response to a train entering said third portion of said stretch of track at said first or said second end respectively, a third traffic responsive relay and a fourth traffic responsive relay each normally energized but becoming deenergized in response to a train on said first or said second track portion respectively, a first and a second signal relay, manually controllable means for energizing each of said signal relays, means for then retaining each of said first and said second signal relays energized controlled by said third or said fourth traffic responsive relay respectively in the energized condition and also controlled by manually operable means, a first and a second traffic locking relay, a first and a second traffic indication relay, means controlled by said first signal relay in the energized condition and by said second signal relay in the deenergized condition for energizing said second traffic locking relay and said first and second traffic control relays by current of reverse polarity, means controlled by said second signal relay in the energized condition and by said first signal relay in the deenergized condition for energizing said first traffic locking relay and said first and second traffic control relays by current of normal polarity, a pickup circuit for said first traffic indication relay controlled by said first and said third traffic responsive relays in the energized condition, a stick circuit for said first traffic indication relay controlled by said third traffic responsive relay and said first traffic locking relay both in the energized condition, a pickup circuit for said second traffic indication relay controlled by said second and said fourth traffic responsive relays in the energized condition, a stick circuit for said second traffic indication relay controlled by said fourth traffic responsive relay and said second traffic locking relay both in the energized condition, means including back contacts of said first or said second traffic indication relay for energizing said second or said first traffic locking relay respectively and said polar traffic control relays in response to a train on said stretch of track, and means including said first or said second traffic responsive relay for controlling said first or said second signal respectively.

the energized condition for energizing said first traffic indication relay, means controlled by said second traffic responsive relay in the energized condition for energizing said second traffic indication relay, means controlled by said first or second traffic locking relay in the energized condition for then retaining said first or second traffic indication relay respectively energized, a first traffic control repeater relay, a pickup and a stick circuit for said first traffic control repeater relay controlled by a contact of said first traffic control relay in the normal position and the pickup circuit also controlled by said first traffic locking relay in the energized condition, a second traffic control repeater relay, a pickup and a stick circuit for said second traffic control repeater relay controlled by a contact of said second traffic control relay in the reverse position and the pickup circuit also controlled by said second traffic locking relay in the energized condition, means controllable by said first signal control means in the normal condition and by said second signal control means in the second condition and by said first and second traffic control repeater relays in the energized and deenergized conditions respectively for energizing said first traffic locking relay and said polar traffic control relays by current of a given normal polarity, means controllable by said first signal control means in the second condition and by said second signal control means in the normal condition and by said first and second traffic control repeater relays in the deenergized and energized conditions respectively for energizing said second traffic locking relay and said polar traffic control relays by current of the opposite or reverse polarity, means including said first traffic control repeater relay and said first traffic indication relay both in the deenergized condition for energizing said second traffic locking relay and said traffic control relays by current of reverse polarity in response to a train on said stretch of track, means including said second traffic control repeater relay and said second traffic indication relay both in the deenergized condition for energizing said first traffic locking relay and said traffic control relays by current of normal polarity, and means including said first and second traffic responsive relays for controlling said first and second signals respectively.

45 6. In combination, a stretch of railway track, a first and a second signal adjacent the opposite ends of said stretch for governing traffic movements in opposite directions onto said stretch, a first and a second polar traffic control relay each having polar contacts which when the corresponding relay becomes deenergised remain closed in the normal or the reverse position to which they were last previously operated in response to current of normal or reverse polarity respectively, first manually controllable signal control means and second manually controllable signal control means each having a normal condition and each manually operable to a second condition, a first traffic locking relay, a second traffic locking relay, a first traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train entering said stretch of track at said first or said second signal respectively, a first and a second traffic indication relay, means controlled by said first traffic responsive relay in the energized condition for energizing said first traffic indication relay, means controlled by said second traffic responsive relay in the energized condition for energizing said second traffic indication relay, means controlled by said first or second traffic locking relay in the energized condition for then retaining said first or second traffic indication relay respectively energized, a first traffic control repeater relay, a pickup and a stick circuit for said first traffic control repeater relay controlled by a contact of said first traffic control relay in

the normal position and the pickup circuit also controlled by said first traffic locking relay in the energized condition, a second traffic control repeater relay, a pickup and a stick circuit for said second traffic control repeater relay controlled by a contact of said second traffic control relay in the reverse position and the pickup circuit also controlled by said second traffic locking relay in the energized condition, means controllable by said first signal control means in the normal condition and by said second signal control means in the second condition and by said first and second traffic control repeater relays in the energized and deenergized conditions respectively and also by said second traffic indication relay in the energized condition for energizing said first traffic locking relay and said polar traffic control relays by current of given normal polarity, means controllable by said first signal control means in the second condition and by said second signal control means in the normal condition and by said first and second traffic control repeater relays in the deenergized and energized conditions respectively and also by said first traffic indication relay in the energized condition for energizing said second traffic locking relay and said polar traffic control relays by current of reverse polarity, means including said first traffic control repeater relay and said first traffic indication relay both in the deenergized condition for energizing said second traffic locking relay and said traffic control relays by current of reverse polarity in response to a train on said stretch of track, means including said second traffic control repeater relay and said second traffic indication relay both in the deenergized condition for energizing said first traffic locking relay and said traffic control relays by current of normal polarity, and means including said first and second traffic responsive relays for controlling said first and second signals respectively.

7. In combination, a stretch of railway track, a first and a second signal adjacent the opposite ends of said stretch for governing traffic movements in opposite directions onto said stretch, a first and a second polar traffic control relay each having polar contacts which when the corresponding relay becomes deenergized remain closed in the normal or the reverse position to which they were last previously operated in response to current of normal or reverse polarity respectively, first manually controllable signal control means and second manually controllable signal control means each having a normal condition and each manually operable to a second condition, means controllable by said first signal control means in said normal condition and by said second signal control means in said second condition for energizing said traffic control relays by current of normal polarity, means controllable by said first signal control means in said second condition and by said second signal control means in said normal condition for energizing said traffic control relays by current of reverse polarity, a first traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train entering said stretch of track at said first or said second signal respectively, a first block repeater relay, a second block repeater relay, means controlled by a contact of said first traffic control relay in the reverse position and by said first traffic responsive relay in the energized condition for energizing said first block repeater relay, means controlled by a contact of said first traffic control relay in the reverse position for then retaining said first block repeater relay energized, means controlled by a contact of said second traffic control relay in the normal position and by said second traffic responsive relay in the energized condition for energizing said second block repeater relay, means controlled by a contact of said

second traffic control relay in the normal position for then retaining said second block repeater relay energized, means including said first block repeater relay in the energized condition for controlling said first signal, and means including said second block repeater relay in the energized condition for controlling said second signal.

8. In combination, a stretch of railway track, a first and a second signal adjacent the opposite ends of said stretch for governing traffic movements in opposite directions onto said stretch, a first and a second polar traffic control relay each having polar contacts which when the corresponding relay becomes deenergized remain closed in the normal or the reverse position to which they were last previously operated in response to current of normal or reverse polarity respectively, first manually controllable signal control means and second manually controllable signal control means each having a normal condition and each manually operable to a second condition, a first traffic locking relay, a second traffic locking relay, a first traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train entering said stretch of track at said first or said second signal respectively, a first and a second traffic indication relay, means controlled by said first traffic responsive relay in the energized condition for energizing said first traffic indication relay, means controlled by said second traffic responsive relay in the energized condition for energizing said second traffic indication relay, means controlled by said first or second traffic locking relay in the energized condition for then retaining said first or second traffic indication relay respectively energized, means controllable by said first signal control means in the normal condition and by said second signal control means in the second condition for energizing said first traffic locking relay and said traffic control relays by current of normal polarity, means controllable by said second signal control means in the second condition and by said second signal control means in the first condition for energizing said second traffic locking relay and said traffic control relays by current of reverse polarity, means including said first traffic indication relay in the deenergized condition and said second traffic indication relay in the energized condition and also said second manually controllable signal control means in the normal condition for retaining said second traffic locking relay and said polar traffic control relays energized by current of reverse polarity in response to a train on said stretch of track, means including said first traffic indication relay in the energized condition and said second traffic indication relay in the deenergized condition and also said first manually controllable signal control means in the normal condition for retaining said first traffic locking relay and said polar traffic control relays energized by current of normal polarity in response to a train on said stretch of track, and means including said first or second traffic responsive relay for controlling said first or second signal respectively.

9. In combination, a stretch of railway track, a first and a second signal adjacent the opposite ends of said stretch for governing traffic movements in opposite directions onto said stretch, a first and a second polar traffic control relay each having polar contacts which when the corresponding relay becomes deenergized remain closed in the normal or the reverse position to which they were last previously operated in response to current of normal or reverse polarity respectively, first manually controllable signal control means and second manually controllable signal control means each having a normal condition and each manually operable to a second condition, a first traffic locking relay, a second traffic locking relay, a first traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train entering said stretch of track at said first or said second signal respectively, a first block repeater relay, a second block repeater relay, means controlled by a contact of said first traffic control relay in the reverse position and by said first traffic responsive relay in the energized condition for energizing said first block repeater relay, means controlled by a contact of said first traffic control relay in the reverse position for then retaining said first block repeater relay energized, means controlled by a contact of said second traffic control relay in the normal position and by said second traffic responsive relay in the energized condition for energizing said second block repeater relay, means controlled by a contact of said

traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train entering said stretch of track at said first or said second signal respectively, means including said first signal control means in the normal condition and said second signal control means in the second condition for energizing said traffic control relays by current of normal polarity, means including said first signal control means in the second condition and the second signal control means in the first condition for energizing said traffic control relays by current of reverse polarity, means including said first traffic responsive relay in the deenergized condition and said second manually controllable signal control means in the normal condition for retaining said traffic control relays energizing by current of reverse polarity in response to a train on said stretch of track, means including said second traffic responsive relay in the deenergized condition and said first manually controllable signal control means in the normal condition for retaining said traffic control relays energized by current of normal polarity in response to a train on said stretch of track, and means including said first and second traffic responsive relays for controlling said first and second signals respectively.

10. In combination, a stretch of railway track, a first and a second signal adjacent the opposite ends of said stretch for governing traffic movements in opposite directions onto said stretch, a first an a second polar traffic control relay each having polar contacts which when the corresponding relay becomes deenergized remain closed in the normal or the reverse position to which they were last previously operated in response to current of normal or reverse polarity respectively, first manually controllable signal control means and second manually controllable signal control means each having a normal condition and each manually operable to a second condition, a first traffic locking relay, a second traffic locking relay, a first traffic responsive relay energizable by means controlled by contacts of said traffic control relays in the reverse position, a second traffic responsive relay energizable by means controlled by contacts of said traffic control relays in the normal position, each of said first and second traffic responsive relays becoming deenergized in response to a train

5 entering said stretch of track at said first or said second signal respectively, a first traffic control repeater relay, a pickup and a stick circuit for said first traffic control repeater relay controlled by a contact of said first traffic control relay in the normal position and the pickup circuit also controlled by said first traffic locking relay in the energized condition, a second traffic control repeater relay, a pickup and a stick circuit for said second traffic control repeater relay controlled by a contact of said second traffic control relay in the reverse position and the pickup circuit also controlled by said second traffic locking relay in the energized condition, means controllable by said first signal control means in the normal condition and by said second signal control means in the second condition and by said first and second traffic control repeater relays in the energized and deenergized conditions respectively and also by said second traffic responsive relay in the energized condition for energizing said first traffic locking relay and said polar traffic control relays by current of a given normal polarity, means including said second traffic responsive relay and said second traffic control repeater relay both in the deenergized condition for retaining said first traffic locking relay and said polar traffic control relays energized by current of normal polarity, means controllable by said first signal control means in the second condition and by said second signal control means in the normal condition and by said first and second traffic control repeater relays in the deenergized and energized conditions respectively and also by said first traffic responsive relay in the energized condition for energizing said second traffic locking relay and said polar traffic control relays by current of reverse polarity, means including said first traffic responsive relay and said first traffic control repeater relay both in the deenergized condition for retaining said second traffic locking relay and said polar traffic control relays energized by current of reverse polarity, and means including said first and second traffic responsive relays for controlling said first and second signals respectively.
